UNITED STATES PATENT OFFICE.

MILES O. STANLEY, OF SOUTH DANVERS, MASSACHUSETTS.

METALLIC BRIDLE-WINKER.

Specification forming part of Letters Patent No. 44,121, dated September 6, 1864.

To all whom it may concern:

Be it known that I, MILES O. STANLEY, of South Danvers, in the county of Essex and State of Massachusetts, have invented a new and useful Metallic Bridle-Winker; and I do hereby declare that the following is a full, clear, and exact description of the construction and operation of the same, reference being had to the accompanying drawings, forming a part of this specification, in which—

Figure 1 is a side view of one of my winkers attached to the head strap, and Fig. 2 is a section in the line *x y* of Fig. 1.

Like parts are indicated by the same letters in both figures.

The nature of my invention consists, first, in constructing bridle-winkers entirely of metal instead of leather, whereby I am enabled to produce a much cheaper and better article, lighter, stiffer, and more durable than any known or used before; and, second, in attaching the winker to the head-strap by means of rivets instead of sewing, thereby saving a great amount of labor and expense.

To enable others skilled in the art to make and use my invention, I will now describe its construction and operation.

I construct the winker A of iron, steel, brass, copper, zinc, or other suitable metal or alloy, and of any desirable size and shape. When made of sheet metal, it may be very thin, the requisite stiffness being imparted to it by embossing or "striking up" a ridge, f, extending around it, as represented in Fig. 1; or the whole body may be made convex, or covered with embossed designs of any description for the sake of ornament as well as stiffness. I prefer sheet metal "struck up" or embossed, some kinds of metal, however, might be cast in the shape required.

In order to give the winkers the appearance of leather, I propose, as a general thing,

to cover them with black japan or other suitable paint or varnish, which also prevents the metal from corroding, or some kind of metal (as for instance brass and copper) will answer without paint or varnish, in which case the winkers may be kept bright and ornamental by scouring.

I confine the winker to the head-piece B by means of flat-headed rivets d and washer e, as represented in the drawings.

To give additional stiffness to the winker, I bend the edge that laps onto the strap B, as shown at e, Fig. 2, forming a rabbet for the reception of said strap. This, however, is not absolutely necessary, as the overlapping edge may be straight. I prefer, however, to construct it as shown in Fig. 2. By thus attaching the winker to the strap—*i. e.*, by rivets in place of sewing—I obviously save a great amount of labor and expense, riveting being done many times faster than sewing. Again, one of my metallic winkers cut out, "struck up," and painted or varnished will cost not more than one-fourth as much as the leather alone of the ordinary kind of winkers, to say nothing of the sewing required to construct the latter, while at the same time my winkers are lighter, stiffer, and more durable than any known or used before.

Having thus described the construction and operation of my invention, what I claim as new, and desire to secure by Letters Patent, is—

1. Constructing a bridle-winker wholly of metal, substantially as and for the purpose described.

2. Attaching the bridle-winker to the head-strap by means of rivets, substantially as set forth, and for the purpose described.

MILES O. STANLEY.
